UNITED STATES PATENT OFFICE.

HENRY A. GRIFFIN, OF BROOKLYN, NEW YORK.

DESIGN FOR A CARPET.

SPECIFICATION forming part of Design No. 20,829, dated June 9, 1891.

Application filed May 18, 1891. Serial No. 393,219. Term of patent 7 years.

To all whom it may concern:

Be it known that I, HENRY A. GRIFFIN, a citizen of the United States, residing at New York city, in the county and State of New York, have invented and produced a new and original Design for Carpets, of which the following is a specification, reference being had to the accompanying drawing, forming a part thereof, which represents a plan view of a piece of carpet ornamented in accordance with my design.

The design consists of square block-like figures A and A', arranged one above the other and at opposite sides of border figures B, the general appearance caused by the arrangement of the figures simulating a check pattern. The block-like figures A are formed by a series of heavy diagonally-grouped lines a and light straight lines a'. The lines a essentially cover the entire surface, except at

the center, at which point a square a² is formed by the light lines a', the face of the square being covered by diagonal lines a³ of medium width. The block-like figures A' contrast with the figures A and are formed by grouping straight light lines b, crossed by diagonal lines b' of medium thickness. The diagonal lines b' are, however, omitted at the center of the block, at which point a square b² is formed by heavy lines b', arranged diagonally, but in a direction opposite to the direction of the medium heavy lines b'. 25 30

I claim—

The design for a carpet, substantially as herein shown and described.

HENRY A. GRIFFIN.
